US00D859371S

(12) **United States Design Patent** (10) **Patent No.:** **US D859,371 S**
(45) **Date of Patent:** **** Sep. 10, 2019**

(54) **ANTENNA ASSEMBLY**

(71) Applicant: **Airgain Incorporated**, San Diego, CA (US)

(72) Inventor: **Mark Montgomery**, Melbourne Beach, FL (US)

(73) Assignee: **Airgain Incorporated**, San Diego, CA (US)

(**) Term: **15 Years**

(21) Appl. No.: **29/606,667**

(22) Filed: **Jun. 7, 2017**

(51) **LOC (12) Cl.** **14-03**

(52) **U.S. Cl.**

USPC **D14/230**

(58) **Field of Classification Search**

Michael Catania

(57) **CLAIM**

The ornamental design for an antenna assembly, as shown and described.

DESCRIPTION

FIG. 1 is a front elevation view of an antenna assembly;

FIG. 2 is a side elevation view thereof;

FIG. 3 is an opposite side elevation view thereof;

FIG. 4 is a top plan view thereof;

FIG. 5 is a bottom plan view thereof;

FIG. 6 is a rear elevation view thereof; and,

FIG. 7 is a top perspective view thereof.

The broken lines are for illustration purposes only and form no part of the claimed invention.

1 Claim, 7 Drawing Sheets
